UNITED STATES PATENT OFFICE.

JULIUS E. MERRIMAN, OF WEST MERIDEN, CONNECTICUT, ASSIGNOR TO
FOSTER, MERRIAM & CO., OF SAME PLACE.

DRAWER-PULL.

SPECIFICATION forming part of Letters Patent No. 234,139, dated November 9, 1880.

Application filed September 1, 1880. (Model.)

To all whom it may concern:

Be it known that I, JULIUS E. MERRIMAN, of West Meriden, of the county of New Haven and State of Connecticut, have invented 5 a new and useful Improvement in Drawer-Pulls; and I do hereby declare the same to be described in the following specification and represented in the accompanying drawings, of which—

10 Figure 1 is a top view, Fig. 2 a side elevation, and Fig. 3 a longitudinal section, of a drawer-pull of my improved kind. Fig. 4 is a top view of its fastening-screw. Fig. 5 is a front view, and Fig. 6 a vertical section, of the 15 rosette.

In the first three of the said figures the drawer-pull is shown as fixed to a portion of the front of a drawer, such portion being represented at A.

20 The nature of my invention is duly set forth in the claims hereinafter presented.

My improvement relates to the common pendulous drawer-pull, whose knob has its shank hinged to its supporting-screw, in order 25 that the knob, when at rest, may hang vertically from the screw when the latter is fixed in a drawer or other article.

In the drawings, B denotes the knob; C, its sustaining-shank; D, the confining-screw; E, 30 the nut, and F the rosette. The said rosette is to be "struck up" from sheet metal by dies, and therefore necessarily is hollow or chambered, as shown at a.

In carrying out my improvement I form the 35 said rosette or terminate it at its center with a chambered and notched dome, b, the notch c being extended diametrically and horizontally across the arch of the dome, and to receive the rectangular head d of the confining-screw D. The said screw has a prismatic and somewhat tapering shank, e, to prevent it from turning around in the drawer-front after being inserted therein, and such screw also has a rectangular and slotted head, d, formed in 45 top view, as shown in Fig. 4, and in edge view, as shown in Fig. 2. This head extends into and fills the notch c, whereby the notched dome of the rosette is made to aid in preventing both the rosette and the screw from revolving or working loose on the drawer as well as independently of each other.

The rosette and its notched dome, when the nut is set up, operate to keep the screw in its normal position, in order for the knob, when down, to hang vertically.

55 The knob or handle B is fixed upon a flat shank, C, bent at its upper part in manner as represented, so as to form a hook, f, and a back stop, g, projecting from it in manner as represented. The said hook hooks into or 60 upon the slotted head d, and with such constitutes the hinge of the knob, the back stop, g, serving, by contact with the dome b, to prevent the knob from falling against and indenting the drawer.

65 Besides the back stop, the shank C is provided with a fore stop, as shown at h h, to prevent the knob from being raised or thrown upward high enough to stop it from falling by gravity to its lowermost position. The fore 70 stop, by abutting against the upper surface of the head of the confining-screw, stops the knob at its highest position.

In the above-described draw-pull, I claim 75 as my invention as follows, viz:

1. The rosette chambered and provided with the chambered and notched dome, as described, in combination with the knob-shank supporting-screw having its slotted head constructed as described and inserted in the 80 notch of the dome, all being substantially as set forth.

2. The knob-supporting screw hinged to the knob and provided with the slotted head and the prismatic shank, in combination with the 85 nut and with the rosette chambered and provided with the chambered and notched extension or dome and having the screw-head arranged in the notch of the dome, all being essentially as set forth.

90 3. The knob-supporting shank C, provided with the back and fore stops, in combination with the rosette having the notched extension and with the confining-screw hinged to the shank and having its head arranged in the 95 notch of such extension, all being substantially as set forth.

JULIUS E. MERRIMAN.
